P. KOHLOFF

SPARK PLUG AND COIL CONNECTER

Filed May 6, 1922.

Paul Kohloff.
INVENTOR
BY Victor J. Evans

WITNESS: Fred W. Ely.

ATTORNEY

UNITED STATES PATENT OFFICE.

PAUL KOHLOFF, OF MAMARONECK, NEW YORK, ASSIGNOR OF ONE-HALF TO GEORGE W. GROSS, OF MAMARONECK, NEW YORK.

SPARK PLUG AND COIL CONNECTER.

Application filed May 6, 1922. Serial No. 559,111.

To all whom it may concern:

Be it known that I, PAUL KOHLOFF, a citizen of the United States, residing at Mamaroneck, in the county of Westchester 5 and State of New York, have invented new and useful Improvements in Spark Plug and Coil Connecters, of which the following is a specification.

The invention relates to means for connecting spark plugs and coil box of an automobile and the principal object is to provide a device of this nature which shall be simple of construction, consisting of a single part, cheap to manufacture, and highly 10 efficient for the purpose for which it is designed.

Another object is to provide a device of this nature which shall possess a certain springiness tending constantly to force both 15 ends into engagement with the binding post.

Another object is to provide a device of this nature which may be readily modified to place and secure the other without entirely removing the nuts from the binding 20 post.

Another object is to produce a device of this nature having a plurality of apertures each of which is adapted for co-action with a binding post so that a degree of adjustment is provided which is at present not 25 possible.

With these and other objects in view, the invention resides in certain novel construction and combination and arrangement of 30 parts, the essential features of which are hereinafter fully described, are particularly pointed out in the appended claim, and are illustrated in the accompanying drawing, in which:—

40 Figure 1 is a perspective view showing a coil box and spark plugs connected by the present invention.

Figure 2 is a detail view of one of the connectors, *per se*.

45 Figure 3 is a sectional view of the end of one of the connectors constructed to embody also the property of a spark intensifier.

Like characters of reference refer to like parts in all views.

50 Referring to the drawing in detail, 10 represents the coil box of any automobile, and is provided with a plurality of binding posts 11 having caps or nuts 12. A corresponding plurality of spark plugs are indi-

cated at 13 each provided with a binding 55 post 14 and terminal nut 15.

Under present practice insulated wires connect the binding posts 11 with the respective binding post 14, said wires including the members or terminal elements which 60 are soldered to the principal portion of the wire. This form of construction is quite costly, and it not infrequently happens that the insulation burns from these wires causing considerable annoyance and sometimes 65 great damage.

The present invention comprises a metal strip 16 which may be of any suitable and desired width and which is preferably made of some spring metal. The strip is provided with a plurality of apertures 17, the end ones of which communicate with jaws or free openings 18 having teeth 20. If desired the strip may be covered with an insulation coat, although this is not deemed 70 necessary in most cases. As shown in Figure 3 the connectors have been coated with solder as shown at 19, the coating being greatly exaggerated in the drawing so as to illustrate the point. The application of 75 solder as shown gives a greater resistance, and consequently effects the same result as if a spark intensifier were utilized.

In use any one of the apertures 17 may be connected with a respective binding post 11 85 and another of the apertures made to receive a respective one of the binding posts 14. However, when it is desired to put in the connector quickly, the nuts 12 and 15 may be loosened and permits a tight connection between the device and the terminal nuts and the opposite jaws pressed home. The nuts are then screwed back to place. It will be seen that with this construction, 90 the springiness of the member 16 tends constantly to force the jaws into engagement with the respective binding post.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole 100 of my invention limited only by the appended claim.

What is claimed as new is:—

A device for connecting a terminal of a coil box with the respective terminals of a spark plug comprising a single piece of relatively springy metal strip having a plu-

5 rality of apertures arranged near both ends thereof, jaws at the extreme ends of said metal strip and communicating with cer-
tain of said apertures, said metal strip

adapted to be bowed in its connection with the respective terminals for constantly 10 forcing the ends of the strip into engagement with the terminals.

In testimony whereof I have affixed my signature.

PAUL KOHLOFF.
